UNITED STATES PATENT OFFICE.

FRANCIS C. HERSEY, OF WELLESLEY, MASSACHUSETTS, ASSIGNOR TO
HERSEY MANUFACTURING COMPANY, OF SOUTH BOSTON, MASSA-
CHUSETTS, A CORPORATION OF MAINE.

GOLF-CLUB.

No. 826,102.

Specification of Letters Patent.

Patented July 17, 1906.

Application filed October 27, 1905. Serial No. 284,704.

To all whom it may concern:

Be it known that I, FRANCIS C. HERSEY, a citizen of the United States, residing in Wellesley, in the county of Norfolk and State of Massachusetts, have invented certain new and useful Improvements in Golf-Clubs, of which the following is a specification.

My invention relates to golf-clubs, it being especially applicable to drivers.

10 It has for its principal object the provision of an effective implement of this character.

In the accompanying drawings, Figure 1 is a perspective view of a club including one embodiment of my invention. Fig. 2 is a 15 similar view of the head portion, enlarged, the shaft being in sections; and Fig. 3 shows in sectional perspective another form of the invention.

Similar characters designate like parts 20 throughout the several figures of the drawings.

I have here shown for convenience in describing my invention a driver D, though it may be applied to any type of club. It has a head 10, having projecting from it the stem or shank 11, which for the purposes of this invention may be considered as a section of the shaft, which is designated as a whole by the character S and which has also a main section 12, usually of wood, carrying a handle 13.

Connecting the shaft-sections to one another is an intermediate section of a material more resilient and preferably more yielding than the companion sections. This section is shown in Figs. 1 and 2 in the form of a sleeve 14, surrounding the sections of 11 and 12, and may be of rubber vulcanized, so as to give it the requisite springiness. As illustrated, it tapers from its ends toward its center, attaining a maximum diameter near the adjoining ends of sections 11 and 12. It is shown as firmly secured to said sections at its opposite extremities by lashings 15, although it should be noted that the grasp of the yielding material may also assist in maintaining the coöperation.

The adjacent ends of the shaft-sections may be slightly separated to permit lateral movement of the head-section upon the handle-section; but this separation is reduced to a minimum by inclining or curving the opposed faces from one another at 16 toward

the periphery of the shaft, thus avoiding contact tending to arrest deflection.

In the form of my invention illustrated in 55 Fig. 3 of the drawings the connecting section consists of a member 17 of properly resilient metal, fitting alined bores or recesses in the main sections. An external connecting member is also shown, this conveniently 60 consisting of a spiral spring 18, fixed near its outer extremities to the sections 11 and 12.

My improved club presents marked advantages in use, the head yielding upon the shaft when contact with the ball occurs and 65 then sharply moving in the opposite direction by virtue of the resilience of the connecting-section as the stroke is completed. This "following" of the ball by the head greatly increases the range of driving. If the stroke 70 is not made at exactly the proper angle to secure the desired direction of drive, the yield of the head allows it to adapt itself so that the divergence is reduced. Moreover, the shaft is not liable to break in use, and the advantageous results are attained without materially weakening the implement or increasing the expense of manufacture.

Having thus described my invention, I claim—

1. A golf-club comprising a shaft having separate sections, and an intermediate section consisting wholly of a material more yieldable than the remainder of the shaft.

2. A golf-club comprising a shaft having 85 separate sections, and a rubber sleeve connecting these sections.

3. A golf-club comprising a shaft having separate sections and provided with adjacent surfaces inclined from one another toward 90 the periphery of the shaft, and means for connecting the sections.

4. A golf-club comprising a shaft having separate sections provided with adjacent curved surfaces, and a resilient connection 95 between these sections.

5. A golf-club comprising a shaft having separate sections provided with adjacent surfaces inclined from one another toward the periphery of the shaft, and a rubber sleeve 100 connecting the sections.

6. A golf-club comprising a shaft having separate sections, and a spring-sleeve surrounding and connecting the sections and in-

creasing in diameter from its ends toward its center.

7. A golf-club comprising a shaft having separate sections, and rubber sleeve connecting the sections and being of a maximum diameter near the adjacent ends of the sections.

Signed at Boston, in the county of Suffolk

and State of Massachusetts, this 24th day of October, 1905.

FRANCIS C. HERSEY.
